WOMAN'S GARMENT

Myer Attman, Philadelphia, Pa., assignor of one-fourth to Morris Hershson, New York, N. Y.

Application September 9, 1937, Serial No. 162,972

4 Claims.

(Cl. 2—71)

This invention relates generally to women's garments. More particularly, this invention relates to the type of women's garments referred to as combination garments.

5 One of the objects of my invention is to provide a novel construction for feminine combination garments in the general form of a house dress or house coat with pajama features incorporated therein.

10 Another object of my invention is to provide a combination garment of the character described which can be quickly and readily donned and removed and which provides a maximum of concealment for the wearer.

15 Still another object of my invention is to provide an improved garment construction of the character described which shall comprise relatively few and simple parts, which shall be relatively inexpensive to manufacture, easy to assemble, sturdy in construction and which, at the same time, shall be highly practical and efficient.

20 Other objects of this invention will in part be obvious and in part hereinafter pointed out.

The invention accordingly consists in the 25 features of construction, combinations of elements, and arrangement of parts which will be exemplified in the construction hereinafter described, and of which the scope of application will be indicated in the following claims.

30 In the accompanying drawing, in which is shown one of the various possible embodiments of this invention.

Fig. 1 is a front perspective view of a lady's 35 garment embodying my invention, with the front thereof in opened position disclosing the interior construction thereof;

Fig. 2 is a perspective view of the garment 40 illustrated in Fig. 1 but showing the same in closed or fastened position;

Fig. 3 is a perspective view similar to Fig. 2 but 45 illustrating the back view thereof; and

Fig. 4 is an enlarged cross-sectional view taken substantially on the line 4—4 of Fig. 3.

Referring now in detail to the drawing, I have 50 disclosed a garment 10 of the type generally referred to as a wrap-around house dress comprising a back section B, a pair of side sections 12 and 13 attached thereto and a front section F.

The side sections 12 and 13 may be designed so 55 that their free longitudinal edges are substantially contiguously disposed at the front of the garment, or they may overlap, as shown in the drawing, and be provided with suitable releasable fastening means, such as buttons 15, cooperating with suitable buttonholes. The side sections 12 and 13 comprise continuous waist and skirt portions and neck and collar portions of any suitable design. The back section B comprises an upper waist portion 16 and a lower portion 17 attached to said waist portion 16, the said lower

portion comprising a pair of panels 18 and 19 (see Figs. 3 and 4). The front section F comprises an upper waist portion 20 and a lower portion 21 attached thereto, said portion 21 comprising a 5 pair of panels 22 and 23 which may be of substantially the same size and contour of the panels 18 and 19, for reasons which will soon become apparent. In assembling the garment, the outer longitudinal edges of the panels 18 and 22 and of the waist portions 16 and 20 are joined by a continuous seam 24 to the inner longitudinal edge of the side section 12, said seam 24 extending from the lower edge of the garment to the armhole. Similarly, the outer longitudinal edges of the panels 19 and 23 and of the corresponding edges of the waist portions 16 and 20 are joined by a continuous seam 36 to the inner longitudinal edge of the side section 13. The upper edges of side sections 12 and 13 and 10 back waist portion 16 are joined by a pair of 15 seams 25 on the shoulder of the garment, extending from the armhole to the rear of the neckline. The upper edges of the side sections 12 and 13 are designed to meet at the center of the neckline in a seam 26 and to serve as a collar. Above the crotch, the back panels 18 and 19 are 20 joined by a seam 29 running from the crotch 28 to the waist portion 16. Similarly, the front panels 22 and 23 are joined above the crotch 28 by a seam 30 which extends from the said crotch 28 to the lowermost point of the hookless fastener device 31, hereinafter described. The inner longitudinal edges of the panels 19 and 23 are joined by a seam 27, while the inner longitudinal edges of the panels 18 and 22 are joined by a seam 27a. 35 The seams 27 and 27a terminate at a point 28 to form a crotch for the pair of separate leg members thus formed by the panels 18 and 22 and 19 and 23.

The lower edge of the back waist portion 16 40 and upper edge of the back lower portion 17 are joined by a seam 32, while the lower edge of the front waist portion 20 and the upper edge of the front lower portion 21 are joined by a seam 33.

As shown in the drawing, the leg members 45 which are formed by the respective panels 18 and 22, and 19 and 23 may be so constructed and arranged as to simulate a pair of pajama legs.

Tucks 34 may be employed in the front and 50 back sections above and below the seams 32 and 33 to add to the style and fit of the garment. A belt 35 may be employed which extends across the back of the garment at the waist line and may be attached at opposite ends thereof to the seams 24 and 36.

The side sections 12 and 13 may be provided 55 with inner panels 37, disposed adjacent the free longitudinal edges thereof and which extend from the lower edge of the dress to the seam 26. One longitudinal edge of the panel 37 may be fixed to 60

the free edge of the side sections while the other longitudinal edge of each of said panels 37 are adapted to hang free from the lower edge of the garment to a point near the armhole. The panels 5 37 serve to give a tailored appearance to the front of the dress and, when the reverse side of the material employed in making the garment 10 is not identical with the front side of the material, the pattern or design of the material 10 may be presented on the collar 40 which is formed by turning down the side sections 12 and 13 where they encircle the neck. The garment 10 may be provided with suitable armholes to which sleeves 41 are attached. It is noted that the 15 upper edge of the waist portion 21 extends approximately to the armholes.

To don the garment the wearer spreads apart the sections 12 and 13 to open the front of the garment, then places a leg in each of the leg members through the top thereof, after which the garment is pulled upwardly and the arms inserted through the sleeves 41. The side sections 12 and 13 may then be wrapped around in overlapping relationship and fastened at the front 25 in the usual manner, such as, for example, the buttons 15 and cooperating buttonholes. To facilitate the action of stepping into the leg members the front section F of the garment above described, is slit from the top edge of the waist portion 21 downwardly to a point near the crotch 22 and the edges of said slit provided with cooperating hookless fastener elements 31 and a slider 42. It is thus seen that when the slider 42 is pulled downwardly to the lowermost part of the 30 fastener device 31, there will be sufficient room to very easily step into the leg members, after which the slider 42 may be moved upwardly to its original position to hold the pajamas in place.

It is thus seen that I have provided a combination garment construction in which the wearer 40 will be protected against revealment, due to the fact that when worn the leg members always serve as a protective covering even when the side-panels 12 and 13 of the garment 10 are in open 45 position, as shown in Fig. 1.

The garment 10, when viewed from the front as shown in Fig. 2, has the appearance of a neat looking house dress whereas the garment from the back, as shown in Fig. 3, presents an appearance of a pair of lounging pajamas.

If desired, a panel may be stitched to the rear of the garment at the waist and along the side seams so as to cover the leg members, and in this way obtain the effect of a complete house 55 dress both in front and back.

It will thus be seen that there is provided a device in which the several objects of this invention are achieved, and which is well adapted to meet the conditions of practical use.

60 As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a combination house dress and pajama 70 garment, a pair of pajama leg members having a crotch portion, an upper waist and back portion fixed to said leg members, a front upper waist and bust portion fixed to said leg members, a slit disposed at the front of the garment and 75 extending from the top edge of said front bust

portion to a point adjacent the crotch portion of said leg members to facilitate the putting on and removal of the garment, releasable means for closing said slit and a pair of panels extending from the shoulder to the bottom of the pajama legs and attached to the opposite outer sides of said waist and said leg members, said last named panels being adapted to overlap over the entire front of the garment to conceal from view the said leg members and the said front waist portion.

2. In a combination house dress and pajama garment, a pair of pajama leg members having a crotch portion, an upper waist and back portion fixed to said leg members, a front upper waist and bust portion fixed to said leg members, said waist and back portion and said front waist and bust portion being joined to each other by seams disposed at the sides of the garment, a slit disposed at the front of the garment and extending from the top edge of said front bust portion to a point adjacent the crotch portion of said leg members to facilitate the putting on and removal of the garment, releasable means for closing said slit and a pair of panels extending from the shoulder to the bottom of the pajama legs and attached to the opposite outer sides of said waist and said leg members, said last named panels being adapted to overlap over the entire front of the garment to conceal from view the said leg members and the said front waist portion.

3. In a combination house dress and pajama garment, a pair of pajama leg members having a crotch portion, an upper waist and back portion fixed to said leg members, a front upper waist and bust portion fixed to said leg members, a slit disposed at the front of the garment and extending from the top edge of said front bust portion to a point adjacent the crotch portion of said leg members to facilitate the putting on and removal of the garment, releasable means for closing said slit and a pair of panels extending from the shoulder to the bottom of the pajama legs and attached to the opposite outer sides of said waist and said leg members, said last named panels being adapted to overlap at the front of the garment, the bottom edges of said leg members being substantially in the same plane as the bottom edges of said panels.

4. In a combination house dress and pajama garment, a pair of pajama leg members provided with a crotch portion, and having seams at the outer opposite sides thereof, an upper waist and back portion fixed to said leg members, a front upper waist and bust portion fixed to said leg members, a slit disposed at the front of the garment and extending from the top edge of said front bust portion to a point near said crotch portion to facilitate the putting on and removal of the garment, releasable means for closing said slit, said waist and back portion, and said front waist and bust portion being joined to each other by seams disposed at the sides of the garment, said last named seams being in alignment with said leg member seams, and a pair of panels attached to the top edge of said rear upper waist and back portions and to said leg members at said outer side seams and having foldable lapel portions adjacent their upper free longitudinal edges, said last named panels being adapted to overlap at the front of the garment.
